UNITED STATES PATENT OFFICE.

DANIEL S. JAMES, OF NEW MARKET, VIRGINIA.

INVALID-CHAIR.

Specification of Letters Patent No. 14,872, dated May 13, 1856.

To all whom it may concern:

Be it known that I, DANIEL S. JAMES, of New Market, in the county of Shenandoah and State of Virginia, have invented a new and useful Improvement in Invalid-Chairs; and I do hereby declare that the following is a full, clear, and exact description of the construction and operation of the same, reference being had to the annexed drawing, forming part of this specification, in which—

Figure 1 is a side elevation of the chair when adapted to rocking. Fig. 2 is a side elevation when in position for reclining. Fig. 3 is a side elevation when converted into a bed.

Similar characters of reference in the several figures denote the same part of the chair.

The nature of my invention consists in combining with a chair loosely jointed, a curved brace running from the joints of the rockers and front of the chair, and constituting a secondary back piece for giving the requisite stiffness to the chair when in position for rocking, and also acting as a brace when the chair is converted into a couch; the details of construction and operation being as follows.

In the drawing *a* is the side of the chair; *b*, the back piece; *c*, the rocker, and *d* the front piece; these several parts being jointed at *e e' e'' e'''* so as to be capable of moving freely. Jointed with the rockers and the front of the chair at *e*, is the curved brace or secondary back piece *f*, having the position (when the chair is designed as a rocker) shown in Fig. 1; the head *i* resting

upon the cross piece *g* of the back. In this position the piece *f*, effectually braces the several parts of the chair and renders the joints as stiff as if they were rigid, and the chair incapable of adaptation to other purposes.

The arms *h* extend backward to the rockers, as shown in Fig. 1, and when head *i* of brace *f*, is withdrawn from bar *g*, and the back permitted to fall, these arm extensions will reach the ground and become the rear supports of a reclining chair. The front supports are provided by swinging out the piece *l*. Further movement of the joints is prevented by braces *m* on each side. The ends of arm extensions and of piece *l* may be provided with rollers.

By removing braces *m* and allowing the back to fall and the front to rise; and turning out the head piece *n*, a couch is formed, supported by pieces *l* and *n*, and stiffened by brace *f* in contact with bar *p* running through joint *e'*, its head piece *i* pressing against bar *q* of chair back.

What I claim as new and of my own invention and desire to secure by Letters Patent, is—

The construction of invalid chairs of a loosely jointed frame in combination with a brace *f* operating substantially as and for the purposes specified.

In testimony whereof, I have hereunto signed my name before two subscribing witnesses.

DANIEL S. JAMES.
